JOHN J. SCHLOSSER, OF FRANKFORT, INDIANA

BRICK-WRAPPING MACHINE

Application filed September 4, 1926. Serial No. 133,649.

This invention relates to a wrapping machine.

The chief object of the invention is to wrap rolls, bricks or blocks of material such as butter or the like mechanically and automatically without manual engagement.

The chief feature of the invention consists in the progressive feeding of butter blocks or the like to the wrapping machine in pre-determined position and in timed relation with the supplying of the wrapping material and thereafter automatically wrap the article with the wrapping material upon continued movement of the several parts of the machine in cyclic operation and following which the wrapped article is automatically ejected.

The full nature of the invention will be understood from the accompanying drawings and the following description and claims:

In the drawings Fig. 1 is a side elevation of the machine with parts broken away and shown in transverse section. Fig. 2 is a top plan view of the machine with the final folding guide and wrapped carton retainer removed. Fig. 3 is a transverse sectional view taken on line 3—3 of Fig. 1 and in the direction of the arrows and is of the block advancing mechanism. Fig. 4 is a transverse sectional view taken on line 4—4 of Fig. 1 and in the direction of the arrows and is of the power means employed. Fig. 5 is a side elevational view of the double ratchet for securing intermittent step by step movement of the carton supporting wheel. Fig. 6 is a diagrammatic side elevation of parts in section showing the initial positioning of the wrapper and of the block to be wrapped. Fig. 7 is a similar view showing parts in the first wrapping position. Fig. 8 is a similar view showing the same parts in the second wrapping position. Fig. 9 is a similar view of the same parts in the third and fourth wrapping positions. Fig. 10 is a similar view of the same parts in the final wrapping position. Fig. 11 is a view of the same parts showing the block completely wrapped and ready for discharge. Fig. 12 is a side elevation of a wrapping wheel adapted for roll

wrapping. Fig. 13 is a top plan view thereof.

In the drawings 10 indicates a platform upon which is detachably and preferably adjustably mounted a supply framework 11. A pair of said frames is positioned side by side and each terminates in an oppositely positioned slide in the form of an angle iron 12, the same forming an open channel between which is mounted an actuating plate 13 carried by a framework 14 which is mounted on the bearings 15 eccentric to the shafts 16. Each shaft 16 carries a disc 17 upon which is mounted the eccentric crank pin 18. Crank pin 18 and both discs are connected together by the tie-rod 19. One of the shafts 16 mounts a pulley 20 driven by link belt 21 or equivalent means driven by pulley 22 carried by shaft 23, which shaft is mounted in the bearing 24 and is driven through the belt 25 by motor 26 to an adjacent pulley 27 also on shaft 23. The channel supports blocks of butter or the like at the ends. Since butter is cut to the same predetermined length for quarter, half and pound packages or cartons, a fixed width of channel is utilized. Each rotation of shafts 16 cause the butter blocks to be elevated from the channels 12 by the plate 13, carried upwardly and forwardly and thence deposited upon said channels 12 and retained thereby during the remainder of the return and lowering movement of the median member 13. In this manner the blocks of butter are advanced along the table or feeding mechanism.

Adjacent the end of the table there is mounted a movable guide 31 which is retractable with a support or platform 32 carried by stem 33 mounted in the guide 34. Said stem 33 terminates in a roller 35 engaging cam 36 carried by and rotatable with shaft 23 and in predetermined relation. Thus, the block of butter at the predetermined time is permitted to advance along the channel and be positioned upon the elevator 32, the block being aligned in proper position by the back plate 37. After the block has been positioned on the platform 32 by the advancing means previously described and the roller has been elevated by means

of the cam 36, the block is held in the elevated position, the same being illustrated in Fig. 1, for a period of time corresponding to the arcuate distance included in the cam 36. While the block is held in this elevated position a pusher bar or plate 40 carried by a stem 42 and adjustably supported in bracket 43 upon a reciprocating lever 44, is adapted to remove the block of butter from the elevator 32 and position the same in the opening or socket 45 of the wheel 50, the specific description of which will be given later.

The shaft 23 includes a crank 46 and the combination link construction 47 through pin 148 is adapted to reciprocate the lever 44 towards and away from the wrapping drum 50. Mounted in the machine framework 49 is a pair of plates 50 which form drums and are carried by the shaft 48. Said plates are apertured as at 45 and are joined together by a pair of parallel socket forming members 47. In the 180 degrees of revolution of the wheel from the loading to the discharge position diametrically opposite therefrom, the wrapped carton successively is supported by the lower face 47, the rear edge 45 of the notch in each of the wheels 50 and the upper face 47, reference being had to Fig. 6.

The open work wheel construction employed is utilized since a pusher plate or ejector 51 is movable from the dotted line shown in Fig. 1 to the full line thereof, said pusher bar being carried by the rod 52 slidably supported in guide 53, and said rod 52 is connected to the bracket 43 and thus simultaneously reciprocable with and to the same degree as the feeding plate 40. Thus plate 51 constitutes an ejector for the wrapped blocks of butter. Positioned adjacent the discharge position is a supporting block 54 and as the blocks are successively discharged they pass on to a belt 55 or other suitable conveying means from which they may be removed and assembled into larger packages.

Between the plate 37 and the wrapping wheel there is provided a trough 56 and as shown clearly in Fig. 6, a sheet of wrapping material such as paper 57, is receivable by said trough and engaged by the block of butter 30 when the block of butter 30 is projected into the block compartment or socket formed by the recesses 45 and plates 47. Thus three sides of the block are simultaneously covered. This is shown in Fig. 7. Thereafter the wrapping wheel is rotated a slight arcuate distance clockwise and as a result thereof the lower projecting edge 58 of the paper 57 is caused to lie against the unwrapped face of the butter carton. Simultaneously therewith the paper adjacent the opposite and lower ends of the butter block is engaged by the tongues 59 and a part of the end wrap is obtained. Thereafter, see Fig. 9, the rotation of the wheel is reversed and in the reversal

the upper free end 60 engages the cam or tongue 61 and is caused to lie adjacent the other folded end and complete the wrapping along the sides. Simultaneously with this movement the tongue 62 engages the opposite portion of the wrapping from that engaged by the tongue 59 and forms the opposite fold which lies adjacent that formed by said tongue 59. Continued rotational movement in a counterclockwise position of said wheel thereupon causes the back portion of the end of the wrapper indicated at 63 in Fig. 9, to follow in the slot 64 which is suitably formed so that it will not sever the same from the remainder of the wrapping but will cause the same to lie flat adjacent the two before mentioned folds as shown clearly in Fig. 10. When the carton has reached the position shown in Fig. 10, the tongue 65 engages the remaining flaps which are formed from the two free ends and folds them inwardly and since the slot 166 is not only arcuate but inclined laterally toward the center, said fold gradually passes beneath the plate 66 and thus the entire carton is sealed as shown by the carton in Fig. 11. Thereafter continued rotation of the wheel will position the carton fully wrapped and ready for ejection by the ejector 51.

The mechanism for securing the aforesaid step by step rotation and reversal of the wrapping wheel is shown in Figs. 1 and 5. Rigid with the shaft 48 are a pair of oppositely directed ratchet wheels 70 and 71. Oscillatably mounted on said shaft is a bracket 72 which in one arm yieldingly supports a dog 73 and in another arm yieldingly supports another dog 74, said dogs being oppositely arranged and being associated with the oppositely positioned ratchets, dog 73 cooperating with the ratchet 71 and dog 74 cooperating with ratchet 70. The oscillating bracket 72 is connected by link 75 to a lever 76, the same having an adjustable connection, see Fig. 1 and being fulcrumed at 77. Said lever terminates in a follower 78 positionable in an interior cam 79 having the reversing portion 80, the dwell portion 81, the elevational portion 82 and the lowering or returning portion 83. The dwell portion 80 through the instrumentality of the aforesaid connection, causes the reverse rotation of the wheel from the position shown in Fig. 7 to the position shown in Fig. 8 and the portion 82 causes rotation of the wheel in the counterclockwise direction for the final wrapping of the block. The dwell portion 81 of the cam secures a stationary interval during which the block is projected into the socket for wrapping and the wrapped block is ejected from its supporting recess.

In Figs. 12 and 13 a modified wrapping wheel is illustrated. A roll receiving insert or a U-shaped trough 147 is receivable in the notch 45 and includes a central slot 145 for

ejector passage. Adjacent each end of the trough and extending inwardly is a pair of spring retainers 148 permitting of roll reception but preventing roll rotation thereby insuring wrapping of the roll in the oscillatory movement of the wheel. Said springs are also spaced apart to clear the ejector mechanism and may be formed integral with the U-shaped roll adapter insert, the free ends of the latter having sufficient resiliency to maintain the adapter in pocket 45 by engaging the blades 47 thereof.

10 The invention claimed is:

1. In a wrapping machine, the combination 15 of a wheel including an article receiving pocket, means positioned adjacent the peripheral path of said wheel, additional means positioned adjacent the sides of said wheel for simultaneously engaging an article wrapping for folding the same, means for rotating said wheel for securing said wrapping, and means for rotating said wheel in opposite directions for wrapping.

2. In a wrapping machine, the combination 25 of a pocketed wheel for receiving an article to be wrapped, radially movable means for supplying an article to the pocket thereof and nesting the same therein, stationary means for supporting a sheet of wrapping 30 paper adjacent the pocket and interposed between the article and radially movable means and the wheel for nesting of the paper in the pocket by and with the article, a stationary tongue at opposite ends of the article and adjacent the wheel sides, said tongues and said 35 wrapping sheet supporting means being positioned immediately adjacent each other for simultaneously wrapping one side and both ends of the article, said wheel having movement relative to said tongues and said means 40 for securing the aforesaid wrapping.

3. A wrapping machine of the character 45 as defined by claim 2, characterized by the addition of means at each side of the pocketed wheel for engaging the laterally projecting end of the sheet in the rotation of the wheel for folding the remaining ends of said sheet, and means adjacent the periphery of said 50 wheel for engaging the single radially projecting end of the sheet for wrapping the remaining side of the article.

In witness whereof, I have hereunto affixed
my signature.

JOHN J. SCHLOSSER.
